UNITED STATES PATENT OFFICE.

FRANK G. CARREL, OF WESTERN SPRINGS, ILLINOIS, ASSIGNOR TO CALUMET STEEL COMPANY, OF CHICAGO, ILLINOIS, A CORPORATION OF ILLINOIS.

FENCEPOST.

Application filed March 26, 1924. Serial No. 701,898.

To all whom it may concern:

Be it known that I, FRANK G. CARREL, a citizen of the United States, residing at Western Springs, in the county of Cook and State of Illinois, have invented new and useful Improvements in Fenceposts, of which the following is a specification.

This invention relates to rolled metal fence posts and anchor plates therefor, and consists in the matters hereinafter described and claimed.

In the accompanying drawings—

Fig. 1 is a front view of my improved post complete with anchor plate;

Fig. 2 is an enlarged front view of the post and anchor plate;

Fig. 3 is a vertical sectional view taken on line 3—3 of Fig. 2;

Fig. 4 is a horizontal sectional view taken on line 4—4 of Fig. 2;

Fig. 5 is a horizontal sectional view taken on line 5—5 of Fig. 1;

Fig. 6 is a front view of the post and modified form of anchor plate;

Fig. 7 is a vertical sectional view taken on line 7—7 of Fig. 6;

Fig. 8 is a vertical sectional view taken on line 8—8 of Fig. 6, and

Fig. 9 is a fragmentary side view of the post showing the ledges, to be hereinafter described.

The post 1 of my invention is rolled from metal stock, as steel, into T bar and has a front flange 2 and an integral mid-web or rear flange 3 extending from end to end of the post. During the rolling operation, a row of studs or lugs 4 are integrally formed on the front flange 2 and these lugs project outward from said flange a distance greater than the diameter of the fence wires 5, 5 received between them to prevent said wires shifting up or down the post or moving over them when fastened against the post between the lugs by the fence wire fasteners 6, 6.

The studs or lugs 4, 4 are formed in a row from end to end of the post and are spaced relatively close together to provide individual spaces for the fence wire. The lugs 5 or studs 4 being closely spaced provides an individual space for each cross wire in most all fence wire spacing, and thus holds each fence wire from undue shifting up or down the post.

The ground anchor is in the form of a

steel or other metal plate 7 generally flat throughout its major portion and when applied to the post against its front flange 2 has portions on opposite sides thereof, as shown in Figs. 2 and 4. To accommodate the plurality of closely spaced studs or lugs 4, 4 at the plate 7, when applied to the post, said plate is provided with a portion 8 pressed outward from the body of the plate to form a channel to receive these studs, thus allowing the plate to be brought into close contact with the front flange 2 of the post without perforating the plate for the studs. The channel section 8 straddles the studs 4 and extends along the plate from its upper 65 to its lower edges.

A metal clip 9 is employed to firmly hold the plate 7 on the front flange 2 of the post. Said clip 9 lies in front of the plate 7 between its upper and lower edges and has its 75 prongs 10, 10 extending through holes 11, 11 in the plate on opposite sides of the post. The prongs 10, 10 of the clip 9 extend to the rear of the front flange 2 at its side edges and are bent back over the rear face of said 80 flange, as shown in Fig. 4.

The channel section 8 of the plate 7 is cut to provide a cross slot 12 to receive the body of the clip 9 and allow it to cross the channel section without bending or lying away 85 from the plate. Said slot 12 is approximately as wide as the spacing between the lugs or studs 4 so that when registering with the space between two of the lugs it permits the body of the clip 9 to enter between them and be held thereby from shifting up or down the post, as shown in Fig. 3. The clip 9 may be made half round so as to lie flat against the plate 7. The holes 11 may be given a like shape.

The post 1 being rolled to finished form with its row of studs or lugs 4, 4 running from end to end thereof allows the post to be rolled in long lengths which may be cut to the lengths required for fence posts and have their ends pointed for driving into the ground on erection. Attaching the anchor plates 7 is all that is required to complete the posts for the market and that may be done at the factory or mill where the posts are rolled and cut to lengths. Providing the plate 7 with a channel section 8 allows the plate to be placed at any distance required from the lower end of the post without reference to the lugs or studs 4, 4 on the 100 105 110

post or their spacing because it is not necessary to have holes in the plate for the studs to project through, as heretofore.

In displacing the metal to make the studs 5 or lugs 4 during the rolling operation, the displaced metal forms flat ledges 13 across the spaces between the studs to space the fence wires 5 out of contact with the post flange 2 on opposite sides of the studs, as 10 shown in Fig. 3. These ledges 13 are separated by the lugs 4 between them and keep the fence wires from undue contact with the flange 2.

Instead of the slot 12 cut in the anchor plate 7, the plate may be made as shown in Figs. 6 and 7. As there illustrated, the plate 7^a has a channel section 8^a to receive the studs or lugs 4, 4 behind the same, the same as before. For the clip 9^a, the plate 7^a has 20 a cross-channel 12^a formed in the channel section 8^a by forcing or passing down the metal of the channel section 8^a at the place for the clip to cross the same. This cross-section 12^a lies in the space between two of 25 the studs or lugs 4, 4 at the same, and in addition to the clip 9^a holds the plate against movement or shifting up or down the post.

I claim as my invention:

1. A metal fence post having a front 10 flange, a row of studs or lugs integral with said flange and extending lengthwise thereof, an anchor plate applied against said front flange and having an outwardly projecting portion forming a channel section 15 to straddle the studs or lugs behind the channel and means for securing the plate to said flange.

2. A metal fence post having a front 10 flange, a row of studs or lugs integral with said flange and extending lengthwise thereof, an anchor plate applied against said front flange and having an outwardly projecting portion forming a channel section 15 to straddle the studs or lugs behind the channel and a clip applied against the front of said plate with its prongs extending through the plate and bent around the side edges of

said flange for securing the plate thereto, said channel section having a cross opening to receive the body portion of the clip crossing 50 the channel section.

3. A metal fence post having a front flange, a row of closely spaced studs or lugs integral with said flange and extending lengthwise thereof, an anchor plate applied 55 against said front flange and having an outwardly projecting portion forming a channel section to straddle the studs or lugs behind the channel, and a clip applied against the front of said plate with its prongs extending through the plate and bent around the side edges of said flange for securing the plate thereto, said channel section having a cross slot to receive the body portion of the clip crossing the same, said cross-slot 60 opening through the plate so that the body portion of the clip may lie between two of the lugs behind the plate and in contact therewith on opposite sides of its channel section. 70

4. A metal fence post, comprising a rolled T bar to provide the post with front and rear flanges, a row of studs or lugs formed integral with the front flange during the rolling of the post and projecting outward therefrom, said studs being closely spaced apart, an anchor plate applied to the post against said front flange and having an outwardly projecting portion forming a channel section to straddle the studs or lugs behind the plate, and a clip applied against the front face of said plate with its prongs 80 extending through the plate and bent around the side edges of said front flange for securing the plate thereto, said channel section having a cross-slot as wide as the space between lugs to receive the body portion of the clip and allow the same to lie between the lugs and in contact therewith. 85

In testimony that I claim the foregoing 90 as my invention, I affix my signature this 24th day of March, 1924.

FRANK G. CARREL.
